UNITED STATES PATENT OFFICE.

CHARLES MURTON SEXTON, OF AURORA, ILLINOIS.

PNEUMATIC TIME-SIGNAL FOR RAILWAY-TRAINS.

SPECIFICATION forming part of Letters Patent No. 317,224, dated May 5, 1885.

Application filed November 28, 1884. (No model.)

To all whom it may concern:

Be it known that I, CHARLES MURTON SEXTON, of Aurora, in the county of Kane and State of Illinois, have invented certain new and useful Improvements in Train-Signals for Railways; and I do hereby declare that the following is a full, clear, and exact description of the invention, which will enable others skilled in the art to which it appertains to make and use the same, reference being had to the accompanying drawings, and to letters of reference marked thereon, which form a part of this specification.

The object of my invention is to provide a means whereby the engineer or other officer of a train approaching the signal may discover, by glancing his eye at the dial of the apparatus, just how many minutes since the next preceding train left the place where such signal is placed, and which may be anywhere along the road, and even miles distant from a station, thus giving him accurate information as to whether it was behind or ahead of its time, and consequently governing him in the running of his own train slower or faster as need be to insure safety and avoid running into the train ahead.

It consists in mechanism and appliances, which will presently be described, such that the passing train will actuate through proper instrumentalities the hand or index-pointer to move it to the zero-point on the dial, and of mechanism which, after such train shall have passed, will move such hand or pointer with a steady movement, corresponding in time to the minute-hand of a watch or clock. Thus the engineer of each train running in the same direction not only perceives how far ahead of him in time is the next preceding train; but his train in passing also sets back the pointer to zero to perform a similar duty for the train next to follow.

Figure 1 is a side elevation, showing the signal adapted for two dials; Fig. 2, a vertical section of an apparatus embodying my invention; Fig. 3, a view of a counterbalance-weight; Fig. 4, a face view of the dial and its indicating-hand; Fig. 5, a detail (enlarged) of the metal screw-plug; Fig. 6, a detail (en-

larged) of disk-valve, and Fig. 7 a detail (enlarged) of the piston of the air-pump.

A is a lever of the third order, centered, as shown at *b*, between the rails of the railway-track, and having an upward projection, *c*, which, when this lever is in its proper position to be actuated by the wheels of a locomotive, projects a little above the top line of the rail at its outer side, so that the wheel shall depress the lever. Beneath the other end of this lever is a suitable coiled or other spring, *d*, exerting a constant tendency to press upward this end, and with it, of course, this piece or projection *c*, which should be arched at its upper face, to offer no abrupt obstruction to the passage of the wheel upon and over it. Attached to this same end of the lever is a piston-rod, *e*, and piston *f*, working in a cylinder, *g*, thus constituting an air-pump, the piston having any suitable number of perforations or air-passages *f'*, and any appropriate valve *h*, which may be a disk of leather or rubber placed on top of the piston. Connected to this air-pump cylinder, and near its top, is an air-conducting tube, *j*, which allows air driven out of this pump to be forced into an inverted vessel or can, *k*, closed at top and open at its bottom, and which is inserted in another vessel, *l*, open at top and closed at its bottom, similarly to a gas-holder at a gas-works, the tube *j* passing up through the bottom of the vessel *l* and terminating inside of the inverted vessel *k* at a point above the line of the liquid to be placed in the vessel *l*.

A check-valve or cock, *m*, permits the control of or the cutting off the current of air forced through the pipe or tube *j*.

The vessel *l* is placed or secured on any suitable stationary support, *n*, and the vessel or cup *k* is provided at its top with any appropriate adjustable air valve or cock, and whereby the expulsion or exit of air may be controlled to any degree required. As a convenient form or style of valve, I have shown it as made of a metal screw-plug, *p*, tapering at its lower end, and having a longitudinal diminishing groove, *q*, at one side, serving as the air-passage, and between the head *r* of this plug (and by means of which it is turned for

adjustment) and the top of the part *k* is a rubber piece or block, *s*. The turning of this screw downward closes the air-exit passage to any needed degree, or entirely, if desired, 5 and the turning of it backward serves to graduate the expulsion of the air to the requisite degree, and to control accordingly the consequent descent of the vessel *k*, and this descent actuates the dial hand or hands, as 10 will now be described. The weight of vessel *k* should be somewhat greater than that of the weight *x* on the cord in order to overcome this weight and any resistance due to friction, so that this vessel may be free to descend in 15 the degree that air is permitted to escape from the valve *p*.

Cords *t t'*, attached to the rising and falling part *k*, pass upward, and are each wound several times, but each in an opposite direction, 20 around its respective roller-shaft, to the outer end of each of which shafts (or to one only, if only one dial is needed) is affixed the hand or pointer *u*, an appropriate dial, *v*, being used for each pointer, and marked off with the 25 hours and minutes, like the face of a clock or watch. These cords each leads from its shaft to another shaft placed high enough above it to allow the weight *x*, which is attached to the cords, to descend as low as the rising of the 30 part *k* may require, and without interfering with any of the mechanism. This weight need not be directly above the vessel; but by means of appropriate guide pulleys or rollers may be made to rise and fall off at one side or whenever 35 convenient.

The vessel *l* being supplied with glycerine or other suitable liquid, as above stated, and the apparatus being suitably located at a station in a position where the engineer or officer 40 of an incoming train can plainly see the hand on the dial, the part *k* of the vessel is raised, and the valve, by the aid of an accurate watch, is then so adjusted that the movement of the dial-hand *u*, caused by the slow gravitating 45 descent of the part *k* in the vessel *l*, shall be in exact accord with the movement of the minute-hand of the watch, the minute-marks on the dial each indicating a minute of actual time. The apparatus, after the descent of the 50 part *k* to its lowest point, is now ready, its hand being say, forty-five minutes, and the lever is in position to be moved by the wheels of an arriving train. The locomotive-wheels, by depressing the lever, operate the air-pump 55 valve *f*, and this in turn forces air through tube *j* into the part *k* of the vessel *l*, raising it, as before stated, so that its attached cords move back the pointer to zero. The train having left the apparatus is free to act, and as its 60 pointer moves a minute-mark for every minute, a glance shows to any observer and to the engineer of the next arriving train just how many minutes since the next preceding train left the signal. When this second train 65 leaves, the same operation is repeated, the

wheels again putting the pointer back to zero, and every train does the same, so that a glance always shows how many minutes since the last train left. To illustrate: Suppose train No. 1 leaves at nine o'clock and sets the signal at zero, and that train No. 2 will leave or pass the signal at 9.20, its engineer will then see that No. 1 train has been gone twenty minutes. Let train No. 3 leave at ten o'clock, and the signal will then show that train No. 2 has been gone forty minutes. No. 4, a fast train, leaves, say, at 10.40; but when it reaches the signal it may appear from the signal that train No. 3 has been gone thirty minutes, showing that No. 4 has gained ten minutes on train No. 3. Thus each train can be advised by this signal apparatus of just how many minutes the preceding train is ahead, and whether it is slower or faster than such train, and can determine its own speed accordingly, much to the safety of the traveling public.

The whole train may pass before the lever *A* can rise enough when depressed by the locomotive-wheels to be materially affected by any other wheels of the train, this rising movement of the lever being slow because of the compressed air in the air-pump.

The pointer will move backward as fast as air is forced into the vessel *k*, and the current is checked by the check-valve *m* not being allowed to rise but a very little, or by a cock in the pipe, and in case of a cock this cock will admit air slowly to the vessel *k*.

The cock or valve *p* does not admit air, but permits it to flow out slowly.

It will be understood that I do not limit myself to any particular order of lever, nor to its form, nor to any particular arrangement of counter-balance or weight.

In some cases the lever may be of the first order, its fulcrum being near the outside of one of the railway-tracks and its longer arm or arms serving to lift the rising and falling air-vessel *k* by acting directly upon any suitable bars or rods extending downward from its top. In such case the air-pump and its tube would be dispensed with. I prefer, however, the construction which I have previously described above.

I claim—

1. A railway-signal for indicating to a train approaching the signal the length of time since the last preceding train left the signal, comprising, in combination, a lever operated by a passing train, a rising and falling liquid-sealed air-chamber actuated by connections from said lever, and cords or chains connecting such air-chamber to counterbalancing-weights, and passing around rollers or shafts to which is attached the indicating or signaling hand, substantially as set forth.

2. In a railway-signal for indicating the length of time since the last preceding train left the signal, the combination of a lever operated by a passing train, an air-pump actu-

ated by such lever, an air-tube leading from such pump to a liquid-sealed air-chamber arranged to rise and fall, and weighted cords or chains connected to such chamber and serving 5 to actuate the hand of the signaling-dial, substantially as set forth.

3. In combination with the lever, an air-pump provided with an adjustable valve, the

tube, stationary vessel, rising and falling chamber, and an adjustable valve thereon for 10 controlling at will the exit of air from such chamber, and for the purpose set forth.

CHARLES MURTON SEXTON.
